Primary Examiner — Stacia A Cadmus(74) *Attorney, Agent, or Firm* — Crowell & Moring LLP(57) **CLAIM**

The ornamental design for a wheel or wheel cover, as shown and described.

DESCRIPTION

FIG. 1 is a front view of a wheel or wheel cover according to the design; and,

FIG. 2 is a perspective view thereof.

The broken lines in the drawings illustrate environmental subject matter only and form no part of the claimed design. Also enclosed is a set of photographs of an embodiment of the design.
